UNITED STATES PATENT OFFICE.

ALBERT A. SELDEN AND WILLIAM G. DUCKETT, OF BALTIMORE, MD.

AUTOMATIC FAN.

SPECIFICATION forming part of Letters Patent No. 253,894, dated February 21, 1882.

Application filed September 30, 1881. (No model.)

To all whom it may concern:

Be it known that we, ALBERT A. SELDEN and WILLIAM G. DUCKETT, citizens of the United States of America, residing at Baltimore city, in the State of Maryland, have invented certain new and useful Improvements in Automatic Fans; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Our invention relates to improvements in automatic fans; and the object is to construct a fan to be used in dining-rooms, bed-rooms, or any place where persons desire to work, read, sleep, or anything, especially in hot weather, 20 without being annoyed by flies, mosquitoes, or other insects, while at the same time being kept cool and comfortable.

The invention consists in the construction and arrangement of parts, as will be more fully described hereinafter, reference being had to the accompanying drawings and the letters of reference thereon.

In the accompanying drawings, Figure 1 is a side view of our automatic fan. Fig. 2 is a 30 view of the case with the fan for application to a student-lamp or bed.

In the drawings, A represents a suitable clock-work, of any desired size and strength, by which the fan is to be operated. This clock-work may be driven by a spring, weight, or other power, and is preferably placed and secured in a casing, B. The casing may, if desired, be provided with a lug, C, as shown in Fig. 2, by which it can be attached to the standard D of 35 a student-lamp; or it may have two lugs, b, (shown in dotted lines,) by which it may be secured to the head-board of a bed, the side of a wall, or any other suitable place. When used on the standard of a student-lamp the set-screw c holds it in any desired height. The 40 case may also be made very ornamental, and can be made of any material and strength to suit different circumstances.

The driving-shaft a of the clock mechanism 45 A, by means of the spring E, wound up as in

any ordinary clock, gives motion to the intermediate gearing until it reaches the shaft e, which imparts motion to the automatic fan F. The shaft e is provided with a crank, f, to which the link or connecting-rod G is attached, 55 and it connects with an eye, g, secured to the stem or handle H of the fan. The handle is provided with a small transverse shaft, h, journaled in a double bracket or standard, I, and at its lower end is secured a counterbalance-weight, i, which assists in helping or throwing the fan over the dead-centers as the fan oscillates backward and forward.

The weight may be made adjustable, and can be made lighter or heavier to suit circumstances.

The fan may be made adjustable to move quicker or slower, as desired, and may be also ornamented and larger or smaller.

Instead of the spring, a suitable weight and 70 cord may be employed.

The case can be readily secured in any desired position, according to the place and the object for which it is to be used, and the fan can be placed so as to move in a horizontal or 75 vertical direction.

The transverse shaft h may be made to enter one of the perforations k in the handle H of the fan, by which a quicker or slower or a more rapid or slower motion is imparted to it, 80 as desired.

The operation will be readily understood by any one, and, being very simple, will need no further explanation here.

As stated, the case can be made very pretty 85 and attractive, and very light, according to the metal or other material employed in its construction, being made either of metal, wood, papier-mâché, vulcanized rubber, or any other desired material.

The device is very simple in its construction and not easy to get out of order, and can be easily wound up by any one familiar with winding up clocks, &c.

Having thus described our invention, what 95 we claim, and desire to secure by Letters Patent, is—

1. In an automatic fan, the combination of the clock mechanism having a motive-power-imparting shaft, e, provided with a crank, f, 100

with a connecting-rod, G, bracket I, and a counterbalanced fan, F, substantially as shown and specified.

2. In an automatic fan, the clock mechanism A, having the motive-power-imparting shaft e, provided with a crank, f, in combination with the casing B, connecting-rod G, bracket I, and a counterbalanced fan, F, all arranged substantially as shown and described.

3. The automatic fan herein described, consisting of the clock mechanism A, having the motive-power-imparting shaft e, provided with a crank, f, to which the connecting-rod G is at-

tached and connects with the pivoted fan F, having transverse adjustable shaft h and counterbalance-weight i, journaled in bracket I, and the case B, all constructed and arranged for operation substantially as shown and hereinbefore set forth.

In testimony whereof we affix our signatures in presence of two witnesses.

ALBERT A. SELDEN.

WM. G. DUCKETT.
